UNITED STATES PATENT OFFICE.

OSMOND W. OLMSTED, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,268,605.

Specification of Letters Patent.

Patented June 4, 1918.

Application filed October 3, 1912. Serial No. 723,677.

To all whom it may concern:

Be it known that I, OSMOND W. OLMSTED, a citizen of the United States, residing in Hartford, in the county of Hartford and State of Connecticut, have invented certain new and useful Improvements in Combined Type-Writing and Computing Machines, which the following is a specification.

10 This invention relates to a computation accumulating set of a type useful in connection with the Hanson computing machine such as that described in Patent No. 905,421, dated December 1, 1908.

15 In the Hanson machine above mentioned, pins representing digits are set up or indexed on rack bars to afford a preliminary representation of a computation, whereby the extent which these rack bars will subsequently rotate the computing or dial

20 wheels is determined.

A feature of this invention is to provide a new method of setting or indexing the pins or other digit-representing elements

25 whereby a simple and compact structure is afforded, which occupies a minimum of space and acts with a minimum of movement.

A further feature of this invention is the improvement in the means for retaining the pins on the rack bars so that they will not become accidentally disengaged therefrom no matter in what position the bar is held.

In carrying out these and further features, the pins are provided with cam surfaces, and swinging linkages are provided with cam lugs arranged to cam down by a transverse movement the apposite pin on any one of the pin bars which happens to be raised. The pins are held from coming out of their sockets in each of the bars by a retaining flange common to all of the pins on a bar and entering into a cut-out portion to engage a shoulder. This flange also determines the limit of upward movement of the pins.

Other features and advantages will hereinafter appear.

In the accompanying drawings,

50 Figure 1 is a vertical section taken from right to left of the machine, and showing one of the pin-bearing rack bars in its

raised position ready to have one of the pins thereon set by one of the pin-setting linkages.

Fig. 2 is an enlarged fragmentary view similar to Fig. 1, showing the pin-setting linkage after having been actuated to depress one of the pins.

Fig. 3 is a skeleton perspective view, showing the relative arrangement of one of the pin-bearing rack bars and one of the pin-setting linkages.

Referring more particularly to the separate parts of this invention as embodied in the form shown in the drawings, 1 indicates a column or order member shown in the form of a rack bar having a rack 2 at its forward end arranged to mesh with a pinion 3 connected to rotate a computing or dial wheel 4. As described in the above-mentioned patent, a series of bars 1 are arranged side by side and are adapted to rotate the accordant computing wheels of a series arranged side by side, variable amounts according to which one of a series of digit-representing members 5, shown in the form of pins suitably mounted on the rack bars, is set or indexed. There are a number of the pins 5 on each rack bar 1, in

fact one less than the exchange value between the order which the particular rack bar represents and the next higher order, this being in the case of the decimal system nine pins. Each of the pins 5 is mounted

85 in a vertical socket 6 so as to be capable of being moved from the raised or normal position shown in Fig. 1 to the depressed or indexing position shown in the case of the pin farthest to the left in Fig. 2. To

90 retain the pins 5 in either adjusted position, they are each provided with one or more annular grooves, preferably in this case two 7, 8, which are engaged by a spring-pressed ball 9 so as to yieldingly hold the

95 associated pin against accidental movement. The pins 4 are prevented from falling through and out at the bottom of the socket 6 by being each provided with an enlargement or head 10 forming a shoulder which

100 engages that portion of the bar 1 surrounding the socket 6 in each case.

In order to prevent the pins from being forced up and out of the socket 6 or in

case the bar should be inverted to prevent the pins from falling out of the socket, there is provided a retainer 11 shown in the form of an elongated angular flange secured 5 lengthwise of the bar 1 in any suitable manner as by being riveted thereto, and having one arm of the flange projecting over shoulders 12 formed on all of the pins by having the head cut away at one side. This 10 forms a retaining means common to all of the pins, which limits their upward movements, and thus prevents them from being forced up entirely out of the sockets 6.

For the purpose of setting the pins 5 on 15 the rack bars 1 the latter are raised *seriatim* in accordance with their denomination or order by mechanism not shown but represented by fingers 13. When a pin-bearing rack bar is raised one of its pins will be 20 set or depressed below its fellows by any one of a series of pin-setting linkages 14 which are operated by associated ones of a set of numeral keys 15. To accomplish this, each 25 of the numeral keys 15 is provided with a thrust rod 16 which, when the connected numeral key is depressed, will rock the associated bell crank 17 by engaging with one arm 18 thereof. This bell crank 18 has another arm 19 which is bifurcated to engage 30 a wrist 20 on the associated one of a series of links 21. The link 21 in each case is pivotally connected at its opposite ends to levers 22 and 23 which are pivotally mounted intermediate their ends and connected 35 together at their opposite ends by means of a link 24. A group of the elements just described, which taken together comprise one of the linkages 14, is held in the normal position shown in Fig. 1 by 40 means of a spring 25 which holds one of the levers 23 against a stop 26. When one of the pin bars is raised to the position indicated by the bar 1^a in Fig. 1, it will bring all of the pins 5 thereon into the path of 45 a series of lugs or projections 27 on the lower links 24 of the pin-setting linkages 14, so that when any one of the numeral keys 15 is actuated and the associated linkage rocked so as to produce a transverse or 50 horizontal movement of the lower link 24, one of the projections or lugs 27 will come in contact with the apposite pin 5. Each of the links 24 is provided with a series of these lugs or projections 27, in fact one for 55 each order or column bar 1, and they are made in the form of cam-shaped teeth so that the sides approaching the pins during the initial longitudinal movement of the link 24 will cam down any raised pins. 60 Of course, in actual practice, only one pin bar will be raised and only one linkage 14 operated, so that by this cross selection only one cam tooth will be in action, and thus only one pin depressed at a time.

65 The pins 5 may be each provided with a

cam surface 28 facing the cam surface of the apposite tooth or lug 27 so as to increase the cam action. In such a case, the cut-out portion of the pins will be provided with a flat face as shown, so that the 70 retainer 11 not only acts as a retaining means, but also as a guard to prevent a rotary motion of the pins, thus maintaining the cam surface thereof always in proper relation with the cam surfaces of 75 the lugs on the linkages.

The rack bars may be held against transverse movement due to the transverse thrust in camming down the pins by one or more guides 30 suitably located to take up the 80 strain.

The operation of the device will be readily understood from the above description. Each of the bars 1 is raised *seriatim* in accordance with their order or denomination, 85 and one of the numeral keys 15 struck for a digit to be computed in the column corresponding to the order bar raised. The key will rock the associated one of the linkages 14, so that the lower link 24 thereof will be given a transverse horizontal movement, bringing the proper one of the cam lugs 27 into engagement with the apposite pin 5 on the raised order bar. The pin thus engaged will be cammed down 90 vertically, below its fellows, so that it will form an obstruction in the path of a general operator 29, which when subsequently operated will advance the rack bar 1 an amount corresponding to the particular pin 95 set, the rack bar in turn rotating the computing wheel 4 a corresponding amount.

The head 10 determines the extent of downward movement of the pin 5 in each case, and the flange 11 determines the extent of upward movement of all of the pins on a rack bar. Each individual pin is held against accidental displacement in both positions by the ball and socket detent.

Variations may be resorted to within the 110 scope of the invention, and portions of the improvements may be used without others.

Having thus described my invention, I claim:

1. The combination with a carrier, of a 115 digit-representing element on said carrier settable from normal to indexing position and having a cut-out portion, and a member on said carrier having a projection engaging in such portion to hold said element against 120 rotation, and to limit its movement in one direction.

2. The combination with a member, of a digit-representing element mounted on said member and settable from normal to indexing position, said element having a shoulder engaging said member to determine the limit of movement of said element in one direction, a flange on said member engaging said element to determine the limit of movement 130

- of said element in the opposite direction, and means for holding said element at either limit of movement.
3. The combination with an order bar, of a series of digit-representing elements mounted on said bar and settable from normal to indexing position, and an angular retaining flange extending lengthwise of said bar and arranged to engage all of said elements to limit the movement thereof and to hold the same against rotation.
4. The combination with a member, of a digit-representing element mounted on said member and settable from normal to indexing position, and a linkage having a cam surface thereon arranged to engage said element to set the same.
5. The combination with a member, of a digit-representing element mounted on said member and settable from normal to indexing position, and a linkage having a cam projection arranged to engage said element to cam it from normal position to indexing position.
6. The combination with a member, of a digit-representing element mounted on said member and settable from normal to indexing position, and a linkage for setting said element having a lug thereon to engage said element, said element having a cam surface in a position to be engaged by said lug so as to enable the camming of said element from normal to indexing position.
7. The combination with a member, of an element mounted on said member and settable from normal to indexing position, a link for setting said element having a movement transverse to the movement of said element, said element and said link having cooperating cam surfaces to enable the setting of said element by the transverse movement of said link.
8. The combination with a member, of an element mounted on said member and settable from normal to indexing position, said element having a cam surface, a linkage for setting said element by engagement with said cam surface, and means for maintaining said cam surface in proper relation with respect to said linkage.
9. The combination with a setting linkage, of a series of parallel bars extending transversely of said linkage, a series of pins movably mounted on each of said bars, so as to be settable from a passive to a determinative position, and means for actuating said linkage, said linkage having a series of teeth thereon arranged to engage corresponding pins on said bars.
10. The combination with a series of horizontally disposed bars, of pins mounted on said bars and settable from normal position to indexing position, a link having a horizontal movement, said link and said pins having co-operating surfaces enabling the horizontal movement of said link to produce a vertical movement of certain of said pins.
11. The combination with a series of settable pins arranged in rows, of a camming member universal to all of the pins of a row and arranged to set any one which happens to be raised above its fellows, by a motion transverse to the direction of setting movement of the pin set.
12. The combination with a series of settable pins arranged in rows, of a saw-toothed member universal to a row of said pins, having a tooth individual to each pin in the row and arranged to set any selected pin in the row with which it co-operates, by a camming action of one of the teeth of said member, due to a motion of said member transverse to the direction of setting movement of the pin set.
13. The combination with a carrier, of a digit-representing element on said carrier settable from normal to indexing position, means to detain said element in normal and indexing positions, said element being provided with a shoulder engageable with said carrier to limit the movement of said element in one direction, and a retaining member on said carrier engageable with said shoulder to limit the movement of said element in the other direction.
14. The combination with a carrier, of a digit-representing element on said carrier settable from normal to indexing position, said element having a shoulder and a cutout portion, said shoulder being engageable with said carrier to limit the movement of said element into indexing position, and a member on said carrier projecting into said cutout portion to limit the return movement of said element into normal position.
15. The combination with a carrier, of a digit-representing element on said carrier settable from normal to indexing position, said element having a shoulder and a cutout portion, said shoulder being engageable with said carrier to limit the movement of said element in one direction, and a member on said carrier having a projection which extends into such portion to prevent rotation of said element, said projection also limiting the movement of said element in the other direction.
16. The combination with a carrier, of a series of digit-representing elements on said carrier settable from normal to indexing position, each of said elements having a cut-out portion provided with a flat face, and a retaining member projecting into the cut-out portions of all of said elements and engaging the flat faces thereof, to limit the movement of said elements in one direction and to hold them against rotation.
17. The combination with a carrier, of a digit-representing element on said carrier settable from normal to indexing position,

and a member on said carrier engageable with said element to limit its movement in one direction and to hold it against rotation during its movement.

5 18. The combination with a carrier, of a digit-representing element on said carrier settable from normal to indexing position, a linkage having a cam surface thereon arranged to engage said element to set the 10 same, and means for constantly maintaining said element in effective position with relation to said cam surface.

15 19. The combination with a carrier, of a digit-representing element on said carrier settable from normal to indexing position, a linkage having a cam surface thereon arranged to engage said element to set the same, and a member engageable with said element to constantly maintain it in effective 20 position with relation to said cam surface and to limit its movement in one direction.

25 20. The combination with a carrier, of a digit-representing element on said carrier having a portion cut out, said element being settable from normal to indexing position, a linkage having a cam surface arranged to engage said element to set the same, and a member engaging in said cut-out portion to 30 constantly hold said element against rotation, whereby said element is constantly

maintained in effective position with relation to said cam surface.

21. The combination with a carrier, of a digit-representing element on said carrier settable from normal to indexing position, 35 said element having a cam surface, a linkage having a cam surface thereon arranged to engage the cam surface on said element to set the latter, and means engageable with said element to constantly maintain the cam 40 surface thereon in position for engagement by the linkage cam surface.

22. The combination with a series of denominational bars arranged side by side, a series of pins settable on said bars and arranged in rows and means for raising any bar, of a camming member universal to all of the pins of a row and arranged to set up from normal to indexing position any one which happens to be raised above its fellows, by a motion transverse to the direction in which said bars extend and to the direction of setting movement of the pin set, and guides for holding the bar, whereon the set pin is mounted, against transverse 55 movement during the setting operation.

OSMOND W. OLMSTED.
